MACHINE FOR MAKING TERMINALS

Adolph W. Heernle, Bronx, N. Y.

Application January 10, 1941, Serial No. 373,967

6 Claims. (Cl. 140—92)

My invention relates to a new and improved machine for making terminals.

One of the objects of my invention is to provide certain improvements on the machine disclosed in U. S. Letters Patent No. 2,230,818, issued February 4, 1941.

Another object of the invention is to provide a machine whereby the planar spiral head of the terminal can be readily formed into a different shape.

Another object of the invention is to provide a simple device which can be used in combination with the machine described in said U. S. Letters Patent No. 2,230,818.

Other objects of the invention will be stated in the annexed description and drawings which illustrate a preferred embodiment thereof, reference being made to the aforesaid U. S. Letters Patent No. 2,230,818 for further details.

Fig. 1 is a top plan view of the improved device.

Fig. 2 is a side elevation of Fig. 1.

Fig. 3 is a detail perspective view which shows the essential parts of the slide members which are elements of the device. In this view the slide members are shown spaced from each other.

Fig. 4 is a sectional view, partially in elevation, on the line 4—4 of Fig. 1.

Fig. 5 is a side view, showing the slide members which are illustrated in Fig. 3, when said slide members are in closed position.

Fig. 6 is a sectional view, partially in elevation, on the line 6—6 of Fig. 5.

Fig. 7 is the same as Fig. 6, save that Fig. 7 shows the final operation in shaping the head H which is shown in Fig. 8, to the head H' which is shown in Fig. 9.

Fig. 8 is a perspective view of a terminal which is made according to the aforesaid Stewart application.

Fig. 9 is a perspective view showing the final shape, according to my invention, of the head H which is shown in Fig. 8.

The device includes a drive shaft 90 at the front or right-hand side of the machine. This shaft is provided with a pulley 93, which is driven by means of a belt 94. Said shaft 90 is also provided with a hand wheel 137. The shaft 90 drives the longitudinal shaft 20, by means of the intermeshing bevel gears 91 and 92. The housing 89 is provided with a bearing 89a for the adjacent end of the longitudinal or main shaft 20. This main shaft 20 is provided with cams 44, 68, 121, 112, whose functions will be later described.

The main shaft 20 drives the countershaft 57a by means of intermediate gears which are located in the housing 89. These gears are not illustrated, as they are conventional per se. The wire-stock W is fed intermittently and forwardly (from left to right) by means of a reciprocating carriage 7, whose laterally spaced side plates are connected by the transverse fastening members 9 and 7a. The part of the wire or stock W which enters the machine is straight and said wire is fed in the direction of its length. This carriage 7 is reciprocated by means of the link 8, which is pivotally connected to said carriage 7. The longitudinal movement of the carriage 7 is guided by the guide members 6, which are rigidly connected to frame 5. The clamping lever 33 is yieldingly urged to turn in the clockwise direction by the spring 35, one end of which is connected to the arm 37, which is rigidly secured to the carriage 7. The clamping lever 33 is pivotally connected at 34 to lugs 32, which are rigidly connected to the top plate of the carriage 7.

When the carriage 7 is slid rearwardly or to the left, the clamping lever 33 can turn and slip relative to the wire W. When the slide carriage 7 is moved forwardly, from left to right, the clamping lever 33 clamps the wire W against the adjacent abutment plate of the carriage 7, so that the wire is then fed forwardly in unison with the forward feeding movement of the slide carriage 7. During the rearward movement of the carriage 7, the wire is held clamped against reverse movement, by clamping means which are located in the casing 38. These clamping means are shown in the aforesaid U. S. Letters Patent No. 2,230,818.

The cam 44 is associated with a cam roll 45, which is turnably mounted on the respective leg 40 of an angular lever 46, which is pivoted at its bottom vertex to the frame of the machine. A suitable spring (not shown) holds the roll 45 in contact with the periphery of the cam 44. The other leg of lever 46 is provided with an adjustable push screw 49, which abuts the head 50 of a horizontally reciprocating plunger, which is thus actuated by means of the cam 44, in order to clamp the wire within the casing 38. The spring 51 yieldingly maintains said plunger in its non-clamping position. The plunger which has the head 50 is not illustrated herein, since this detail is fully illustrated in the aforesaid U. S. Letters Patent No. 2,230,818.

The shaft 57a has a gear 57, which meshes with a speed-reduction gear 58. The winding plate 60

is connected to gear 58, so that winding plate 60 is turned in unison with gear 58, about the central axis of said gear. This plate 60 operates to form the head H on the shank T of the terminal. The connection between the shaft 57a and the winding plate 60 may be the same as that shown in said U. S. Letters Patent No. 2,230,818. The bending lever 65, which is the same in function as the corresponding bending lever described in said U. S. Letters Patent No. 2,230,818, is turned by means of the cam 63 and the cam roll 67.

The front or right-hand face of plate 60 has a boss 63 which has a bore through which wire W is pushed intermittently and forwardly by carriage 7, and said bore has a lateral offset in said boss, into which the end of the wire is bent laterally by lever 65. The plate 60 has a pin 70 which forms head H around said boss, as described in said U. S. Letters Patent No. 2,230,818.

The slide member 109 is provided with a turnable cam roll 114, which contacts with the periphery of the cam 112, so that the slide member 109 is laterally reciprocated. The movement of the slide member 109 is guided by the lateral guides 110a, which are fixed to the frame 5 of the machine. One end of a bar 115 is rigidly secured to the top of the slide member 109. The link 116 is pivotally connected to the bar 115 and to a lever 117. This lever 117 is pivotally connected by the pivot pin 118 to the frame of the machine. A pin 117a projects upwardly from the top surface of the slide member 107 and this pin 117a is located in the slot 117b of the lever 117. The slide members 107 and 109 are therefore simultaneously moved in respective opposite directions. The member 107 is guided by fixed guides 108.

The inner longitudinal face of the slide member 109 is provided with a pair of vertical and longitudinally separated recesses 110. Said inner face also has a longitudinal groove or recess 119, which intersects the vertical recesses 110. The wire is pushed through said longitudinal groove 119. The front vertical edges of the slide members 109 and 107 are provided with die-portions or die-recesses 125. The front lateral faces of the slide members 109 and 107 are respectively provided with transverse grooves 132 and 131. The bent ends of the stripper springs 129 and 128 are respectively located in said grooves 132 and 131. The bottom end of the stripper spring 129 is connected by screw 130 to the respective fixed guide 110a. The bottom end of the spring 128 is connected by a companion screw 130 to the respective fixed guide 108.

The inner longitudinal face of the slide member 107 is provided with a pair of projections 106. As shown in Fig. 4, each projection 106 has a V-shaped recess 106a. When the slide members 109 and 107 are in the closed position which is illustrated in Fig. 5, the vertically spaced tips of each member 106 enter the respective vertical recess 110, so that the wire is clamped at the narrow apex of each respective recess 106a. This narrow apex has substantially a semi-cylindrical shape. The shank T is thus supported at two longitudinally spaced zones. This support is only slightly frictional.

The shank T is thus gripped by the members 106, subsequent to the formation of the head H. The wire is then fed forwardly by carriage 7, in order to space head H from the boss of the winding plate 60. The next operation is to sever the shank T from the wire W. A knife-guide 120a is fixed to the slide member 109 by the members 120b. The knife 120 is slidably mounted in said guide 120a. One end of this knife 120 is provided

with a roll 122, which is maintained in contact with the periphery of the cam 121, by means of a suitable spring (not shown). A cooperating knife member 124 is fixed to the slide 107.

5 The tension spring 123 yieldingly holds the slide member 109 to the inoperative spaced position which is shown in Figs. 1 and 4.

The male die member 105 is fixed to a longitudinally movable slide 108, whose movement is guided by the laterally spaced guide members 101 and 102, which are secured by the screws 103 to the frame 5 of the machine. The guides 100a and 108 are respectively fixed to the frame 5 by the screws 100b and 108a.

15 An arm 96 is pivotally connected at 97 to the frame of the machine. The upper end of arm 96 is pivotally connected to one end of link 99, whose other end is pivotally connected to slide 109. The pivot pin connection between the link 99 and arm 96 is provided with a cam roll 98. The cam 95 of the shaft 90 thus operates the link 99, in order to push the slide 109 and its die 125 into the position shown in Fig. 7, so that the cooperating female die-members 125 of slides 107 and 109, and the male die-member 105 bend the initially-formed head H, into the final shape H'. This final shape H' may be varied as desired, as this depends upon the shapes of the female and male die-members.

20 30 The spring 104, whose right-hand end is connected to the fixed member 104a, yieldingly holds the slide 100 in a position in which the die-member 105 is spaced longitudinally from the die-members 125. The right-hand end of the stripper member 126 is fixed by screws 127 to the fixed member 104a.

35 The rod 135 is connected off-center at 135a to a face of the gear 134, which meshes with a gear 133 of the shaft 90. The function of the reciprocating link 135 is to reciprocate the slide carriage 7 by means of an intermediate lever connection of the type which is shown in the aforesaid U. S. Letters Patent No. 2,230,818.

An important feature of the invention is that 40 the frictional clamping grip which is exerted on the wire by the longitudinally spaced members 106 is sufficiently small, so that the pressure of the male die member 105 can push the shank T towards the rear of the machine and from the position illustrated in Fig. 6, without bending said shank, to the position illustrated in Fig. 7, so that the initially-formed head H is forced into the female die members 125. The knife 120 is then out of the way, so that the shank T can thus be pushed longitudinally in a direction reverse to the direction of the feed of the wire relative to the closed slide members 107 and 109.

45 The completed articles shown in Fig. 9 are discharged through the chute 88a.

The operation of the machine is as follows: 50 After the initially-formed head H has been shaped by the means disclosed in the aforesaid U. S. Letters Patent No. 2,230,818, and after said head H has been pushed into the position shown in Fig. 6 by carriage 7, the slide members 109 and 107 are moved towards each other, into the closed position illustrated in Fig. 6. The movable knife 120 is then reciprocated so as to sever the shank T from the wire W. The bending lever 65 then 55 downwardly bends the part of the wire which projects beyond boss 63, into the lateral slot of said boss. The movable knife 120 is then moved out of the way, and the slide 100 is moved rearwardly towards the closed slide members 109 and 107, which are maintained in closed position.

The male die-member 105 rearwardly pushes the shank T, thus forcing the head H into the die recesses 125, and shaping the head between the female die which is formed by said recesses, and the head of the male die-member 105. The slide members 109 and 107 are then moved away from each other, while the head H' is supported upon the male die-member 105. The die-member 105 is then moved forwardly and longitudinally away from the slide members 107 and 109, and the free end of the stripper 126 strips the completed head H' from the die-member 105, so that the completed die terminal which is shown in Fig. 9, can fall through the chute 88a. The slide members 107 and 109 are then moved away from each other.

The initial shape of the head H may be spiral, as shown, or any other shape.

As shown in Fig. 5, the tips of each member 106 enter the respective recess 110 fairly deeply, but the half round apex of each recess 106a then supports the adjacent part of the straight wire, without substantially bending the wire. There is only enough frictional grip to hold the straight part of the wire against accidental longitudinal movement.

I have shown a preferred embodiment of my invention, but it is clear that numerous changes and omissions can be made without departing from its spirit.

I claim:

1. A machine having feeding-means adapted to feed straight wire intermittently forwardly in a straight line, head-forming mechanism operated while the stock is stationary to wind the front end-portion of the wire into an enlarged head, laterally movable members located at respective opposite sides of said line of feed and movable laterally towards each other to operative position and movable laterally away from each other to inoperative position, said members having die-portions which form a female die-member when said laterally movable members are in operative position, said laterally movable members having wire-holding means adapted to hold the wire behind said head and to permit the rearward movement of the wire, said feeding-means being adapted to feed the wire forwardly after the head-forming mechanism has been operated so that said head is located in front of said laterally movable members while said laterally movable members are in inoperative position, means adapted then to move said laterally movable members to operative position, means adapted then to cut the wire behind said laterally movable members, the head-forming mechanism being then operative to bend the wire which is located at the rear of said laterally movable members, a male die-member, means adapted to force the male die-member towards said female die-member to push the head rearwardly into said female die-member and to shape said head between said female and male die-members.

2. A machine having a feed-device adapted to feed straight wire intermittently forwardly in a straight line, a rotatable head-forming device adapted to wind the front-end portion of the wire into an enlarged head, movable bending means adapted to bend said front-end portion into engagement with said head-forming device, holding members located laterally on opposite sides of said straight wire and movable laterally towards each other to operative position and movable laterally away from each other to in-

operative position, said holding members being located in front of said bending means, said holding members having die-portions at their front faces which form a female die-member

5 when said holding members are in operative position, said holding members having adjacent longitudinal faces, one of said longitudinal faces having a longitudinal straight groove which is adapted to receive the straight wire, said straight 10 groove being intersected by a second groove, the other longitudinal face having a projection which is located to enter said second groove, said projection having a recess in which the wire is supported without bending the wire when the holding 15 members are in operative position, said projection supporting the straight wire sufficiently loosely to permit the rearward movement of the straight wire in said longitudinal groove, a male die-member movable towards and away from 20 said female die-member, cutting mechanism adapted to cut the wire between said bending means and said laterally movable holding members, operating mechanism timed to actuate the parts of the machine to perform the following 25 steps in the following sequence:

a. To feed the straight wire to the head-forming device and to the bending means;

b. To operate the bending means to bend the wire into engagement with the head-forming 30 means;

c. To rotate the head-forming means to wind the head;

d. To feed the straight wire between the spaced holding members until the head is located in 35 front of the spaced holding members;

e. To move the holding members to operative position;

f. To operate the cutting mechanism;

g. To again operate the bending mechanism;

h. To move the male die-member towards the female die-member until the head is shaped between said die-members;

i. To move the male die-member away from the female die-members and to move the holding members to their inoperative position.

3. A device according to claim 2 in which the male die-member is shaped to pull the shaped head out of the female die-member, and a stripper adapted to strip the shaped head from the female die-member.

4. In a machine of the class described, holding members movable towards each other to operative position and away from each other to inoperative position, said holding members having die-portions which form a die-member when said holding members are in operative position, said holding members having adjacent longitudinal faces,

55 one of said faces having a straight longitudinal groove through which straight wire can be fed and also having a plurality of additional grooves which intersect said longitudinal groove, the other longitudinal face having respective projections which respectively enter said additional grooves when said holding members are in operative position, said projections having re-

60 spective recesses in which the straight wire is located and supported without bending said wire when said holding members are in operative position, said projections supporting the wire sufficiently loosely so that the wire can move longitudinally in said longitudinal groove when said holding members are in operative position, said holding members being movable laterally away from each other through a distance which

65 exceeds the maximum width of said die-portion.

70

5. In a machine for shaping the head of a member which has a straight shank, a female die-member which has a recess, a male die-member movable towards the recess of said female die-member and away from the recess of said female die-member, holding means associated with said female die-member and adapted to hold said straight shank with said head spaced outwardly from the recess of said female die-member, said holding means being sufficiently loose so that the pressure of the male die-member against said head moves said head into the recess of said female die-member.

6. In combination, a pair of female die members which are movable towards each other to assembled position and which are movable away from each other, each said die member having a recess at a face thereof and also having a longitudinal groove which communicates with said recess, said recesses being assembled when said female die members are assembled to form a single die-recess, said grooves also being assembled when said die members are assembled to

form a longitudinal passage which communicates with said die-recess, the assembled die members being adapted to support the straight shank of a headed work piece loosely in said longitudinal passage and with the head of said headed work piece spaced outwardly from said die-recess, a punch which is longitudinally movable towards said recess and away from said recess in a longitudinal direction which is parallel to said passage, said punch being shaped to press the head of the work piece into said recess when the punch is moved towards said recess, said punch being also adapted to frictionally hold the finally shaped head and to move the finally shaped work piece out of said female die members when said punch is moved longitudinally away from said female die members, stripping means located external to said die members and adapted to strip the finally shaped work piece from said punch after said finally shaped work piece has been withdrawn wholly from said female die members.

ADOLPH W. HOERNLE.
